(57) **CLAIM**

The ornamental design for a video surveillance camera as shown and described.

DESCRIPTION

1. Video surveillance camera

1.1 : Front

1.2 : Back

1.3 : Top

1.4 : Bottom

1.5 : Left

1.6 : Right

The broken lines and the faded areas depict portions of the video surveillance camera in which the design is embodied that form no part of the claimed design.
